UNITED STATES PATENT OFFICE.

OSCAR ZERK, NOW BY JUDICIAL CHANGE OF NAME OSCAR ULYSSES ZERK, OF CLEVELAND, OHIO, ASSIGNOR, BY MESNE ASSIGNMENTS, TO THE BASSICK MANUFACTURING COMPANY.

LUBRICATING APPARATUS.

Application filed March 14, 1921. Serial No. 452,127.

To all whom it may concern:

Be it known that I, OSCAR ZERK, now by judicial change of name OSCAR ULYSSES ZERK, a citizen of the Republic of Czechoslovakia, residing at Cleveland, in the county of Cuyahoga and State of Ohio, have invented a certain new and useful Improvement in Lubricating Apparatus, of which the following is a full, clear, and exact description, reference being had to the accompanying drawings.

My invention relates to a lubricating apparatus and particularly to a coupling member which may be readily attached to a grease or oil nipple for providing an effective temporary connection between the same and a source of supply.

When lubricant is to be forced to a bearing by means of a connecting member and under pressure, it is desirable that a coupling means be provided which may be quickly applied and readily detached when desired, but which when in place will insure an absolutely tight connection, and it is one of the objects of my invention to provide such a device.

Other objects attained by my invention will be apparent in the course of the following description and will be pointed out in the claims.

In the drawings, Fig. 1 is a central longitudinal section of one embodiment of my invention showing the coupling in place on a nipple; Fig. 2 is a side view of the device; Fig. 3 is an end view looking from the left of Fig. 2; Figs. 4, 5 and 6 are similar views respectively of another embodiment of my invention; and Fig. 7 is a longitudinal section of still another form.

Referring to the parts by reference numerals and particularly to Figs. 1 to 3, the cup member 10, which may be made by the usual drawing and punching processes, is shown as provided with a pipe threaded nipple 11 and adjacent its outer end with the circumferential corrugations 12. At this end the material is turned outwardly, a portion being cut away whereby the flanges 13 are formed, having the slots 14 between them, in which the jaws 20, which will now be described, may project. These jaw members or detents 20 surround the enlarged cup portion of member 10, and their surfaces form, for the greater part of their

extent, sectors of a substantially cylindrical surface. These members are bent radially outward adjacent their inner ends, as shown at 21, so that this portion of each of these members constitutes a substantially cylindrical surface sector with its axis extending at an angle to the axis of the other sector. This relationship is clearly illustrated in Figs. 4 and 7. Adjacent the other ends of the members a portion of the material is cut away from each edge and the remaining portion bent radially inwardly to form the projections 22, which are adapted to extend behind a shoulder on the head of a grease or oil cup G. As shown in Fig. 1, the reduced portion of the detents 20 passes thru the slots 14, as will be seen in Fig. 3. On referring to Fig. 4, in which the same form of detents are illustrated as in Figs. 1 to 3, it will be seen that the members 20 may be rocked about the fulcrum 21 so that the ends 22 may be moved outward or inward radially.

In order to provide for manipulating the detents a sleeve 23 is provided, surrounding the detents and longitudinally movable thereof. This sleeve has a restricted portion 24, which extends inward to contact with the members 20, while toward the end of this sleeve closest to the nipple there are formed two circumferentially extending notches 25, 26 on the interior of the sleeve. These notches are adapted to be engaged by the expanding spring 27, carried by the annular members 28 on the member 10. In order to provide a sealed communication between the grease cup and the interior of the gripper, a washer 30 is slidably mounted within this cup and is adapted to be held in outward position by means of the helical spring 31, which bears at one end upon a shoulder on the cup and at its other end upon a spring seat 32 on the washer.

Referring now particularly to Figs. 4, 5 and 6, the construction of the cup member and jaws is substantially that of Fig. 1. The cup 40, however, of Fig. 4 instead of having portions cut entirely away at its upturned end has a flange 41, which is flaring for the greater part of its extent and has the slots 42 cut therein for receiving the jaws 20. The flange 41 is cupped backwardly to form the cylindrical portion 43, as shown in Fig. 4; which forms a guide for the sleeve

50 slidable thereon. This sleeve is shown as made of two parts having radially inwardly extending portions beaded together, as shown at 51. This radially extending portion furnishes an abutment against which the helical spring 52 bears, the other end of this spring being held in position by flange 53, which as illustrated is in the form of an annular dished ring carried between shoulders on the member 40.

10 It will be seen that in this form of the device the spring 52 tends to hold the sleeve 50 in position to retain the jaws or detents in inward or holding position, and therefore, when it is desired to retain the jaws in open position the operator must hold this sleeve member in the position in which the portion 51 rides upon the flared ends of the retaining members.

20 In the modification shown in Fig. 7, the helical spring 62 is mounted upon the other side of the abutment 51, and upon its other end the spring abuts upon a portion of flange 41. With this arrangement of the 25 spring therefore the detents are normally held in open position, and in order to hold them in the closed position the operator must exert pressure upon the sleeve 50 to move it toward the left from the position 30 shown in Fig. 7.

The arrangement of the washer 30 and retaining means is the same in all of the modifications, and it will be observed that the escape of the washer 30 from the open 35 end of the gripper member will be prevented by the corrugations 12 of the cup.

It will also be seen that the members 28 40 constitute a means to prevent both the sleeve 23 and jaws 20 from being accidentally displaced or removed from one end of the cup. The flanges 13 will serve to prevent displacement of these members from the other end of the cup. In the forms shown in Figs 4 to 7, inclusive, the corresponding members 53 and flanges 41, respectively, will serve in the same manner to prevent loss or displacement of the jaws and sleeves.

45 It will be seen that I have devised a connector which may be very quickly attached to and detached from a grease cup or the like and which when attached will provide a tightly sealed connection therewith.

50 I have also devised a construction which may consist of few and simple metal parts 55 which are of such form as to be adapted to be made rapidly and cheaply by ordinary drawing and punching processes, and to be readily assembled at small expense.

59 While I have described specific embodiments of my invention, it is apparent that 60 many different forms of device, embodying the principles thereof might be made. The foregoing description is therefore to be taken as illustrative of my invention and not as restrictive of its character and scope.

Having thus described my invention, I claim:

1. In a device of the class described, a cup having a slotted flange on one end, jaws in said slots, and having portions extending within the circumference of said cup and movable radially with relation thereto, whereby the device is adapted for connection with another member. 70

2. In a device of the class described, a cup, independently mounted jaw members in the form of the sector of a cylinder surrounding said cup, and each having a flared end, whereby they may be rocked thereon, and means for rocking said members acting on said flared ends. 80

3. In a device of the class described, a cup, cylindrical members in the form of cylindrical sectors extending coaxially with said cup when in one position and surrounding said cup, and each having a flared end, whereby they are adapted to be rocked radially thereof, and means for rocking said members. 85

4. In a device of the class described, a cup, an outwardly extending flange on the end thereof, retaining members fulcrumed on said cup and extending thru slots in said flange, and means for rocking said members on their fulcrums, whereby the retaining end thereof is movable radially of said cup. 90

5. In a device of the class described, a cup, cylindrical sector jaw members surrounding said cup and each having a flared end, and means for rocking said members radially of said cup, said means comprising a sleeve longitudinally slidable on said members and having a circumferentially extending portion in contact therewith. 100

6. In a device of the class described, a cup, a washer slidably mounted therein, independently mounted, movable, jaw members pivotally mounted on said cup without said washer, means for moving said jaw members radially thereof including a slidable sleeve engaging the jaw members, and a spring for holding the washer in outward position. 105

7. In a device of the class described, a cup having a slotted flange on its ends, jaws in said slots and radially movable with relation to said cup, a washer in said cup and a spring for forcing said washer toward said jaws. 115

8. In a device of the class described, a cup, sector cylindrical jaw members surrounding said cup and having a flared end, means for rocking said members radially of said cup, comprising a sleeve longitudinally slidable on said sectors and having circumferentially extending members in contact therewith, and means for holding said sleeve in adjusted position. 125

9. In a device of the class described, a cup, jaws pivotally mounted thereon, a sleeve surrounding said jaws for rocking the same, 130

and means comprising grooves in the sleeve and an expansible annular ring carried by the cup for retaining said sleeve in adjusted position.

5 10. In a device of the class described, a cup, independently mounted jaw members pivotally mounted thereon, means for rocking said jaw members comprising a sleeve having a member contacting therewith, and a spring for retaining said sleeve and jaws in one position.

10 15. In a device of the class described, a cylindrical cup, a radial flange at one end, sector cylindrical members mounted on said cup co-axial therewith and extending through slots in said cup, and having their ends bent inwardly to form jaws at one end and flaring outwardly at their other ends to form a fulcrum on which they may be rocked 20 and a sleeve surrounding said members for rocking them.

20 12. In a device of the class described, a

cup, cylindrical sector members surrounding said cup and each bent outwardly at one end, and having an inwardly extending retaining portion on its other end, and means for rocking said members radially of said cup, said means comprising a sleeve longitudinally slidable on said sectors, and having circumferentially extending members in contact therewith, and resilient means for holding a head in contact with said retaining portions.

13. In a device of the class described, a cylindrical cup having a flange extending outward therefrom at each end, jaws on said cup and a sleeve surrounding said jaws, said jaws and sleeve occupying the space between said flanges and being retained on said cup by said flanges.

In testimony whereof, I hereunto affix my signature.

OSCAR ZERK.
